UNITED STATES PATENT OFFICE.

HARLEY M. KAYLOR, OF OIL CITY, PENNSYLVANIA.

TABLE-MAT.

No. 928,129.

Specification of Letters Patent.

Patented July 13, 1909.

Application filed April 3, 1908. Serial No. 425,042.

To all whom it may concern:

Be it known that I, HARLEY M. KAYLOR, a citizen of the United States, residing at Oil City, in the county of Venango and State of Pennsylvania, have invented new and useful Improvements in Table-Mats, of which the following is a specification.

My present invention relates to improvements in table mats of the class adapted to be laid upon the surface of a table for the purpose of protecting the polished surface thereof from injury by hot dishes, and it has for its object primarily to provide a mat of this character that is composed of sections corresponding to the usual leaf and end sections of the ordinary extension tables whereby the mat sections may be added or removed as the surface of the table is enlarged or reduced by the addition or removal of the leaf sections, the mat sections being preferably provided with means at their adjoining edges for securing the sections in proper relation.

Another object of the invention is to provide an improved mat of this character wherein the sections are each composed of a series of narrow slats, preferably asbestos, flexibly united by fabric facings whereby the sections may be conveniently rolled up into small space for storage when not in use or for shipment.

A further object of the invention is to provide covers for the mat sections, these covers serving to protect the sections from soiling, and the covers being removable to permit laundering thereof when soiled.

To these and other ends, the invention consists in certain improvements, and combinations and arrangements of parts, all as will be hereinafter more fully described, the novel features being pointed out particularly in the claims at the end of the specification.

In the accompanying drawing:—Figure 1 is a plan view of a table mat made up of sections constructed in accordance with my present invention, portions of the covers being removed to show the construction of the mat sections; Fig. 2 represents an enlarged sectional view through portions of two adjacent sections; Fig. 3 is a plan view of the mat sections showing the covers removed therefrom; Fig. 4 is an edge view partly in section showing one of the mat sections partially rolled; Fig. 5 is a perspective view of a corner of one of the end sections of the

mat; and Fig. 6 is a perspective view of one of the intermediate sections, a portion of the fabric being broken away to illustrate the interior construction thereof.

Similar parts are designated by the same reference characters in the several views.

Table mats constructed in accordance with my present invention are adapted for use generally in connection with tables of various kinds, and the outline of the mat or the sections thereof may be varied to conform to the shape of the table tops in connection with which the mat may be used.

The present embodiment of the invention is particularly adapted for use in connection with the well known extension tables wherein the end sections are capable of separation so as to lengthen the table, and leaves may be inserted between the end sections in order that the table may be adjusted to the desired size. The mat is made up of sections which correspond to those of the table, and the intermediate sections of the mat may be added or removed according to the adding or removal of the table sections. In the present instance, the mat is composed of a pair of end sections 1 and 2, which, as shown, are rounded to conform to the correspondingly shaped end sections of the table, the end sections of the mat and table in this instance being semi-circular so that when their edges are placed directly together, the mat and table will have a circular form. The mat also embodies one or more intermediate or leaf sections 3 which, in the present instance, are rectangular and conform in size and shape to the corresponding leaf section or sections of the table.

Each section of the mat is made up of a series of slats 4, it being generally preferable to use slats composed of asbestos because of its heat insulating properties. These slats are comparatively thin and narrow, and their longitudinal edges are preferably parallel in order to enable the section to be rolled into a small bundle. These slats are united by a facing 5 preferably of a suitable fabric which covers the upper and lower sides of the slats, and the adjacent longitudinal edges of the slats are separated slightly, and the facing at the upper and lower sides of the slats is stitched together by rows of stitching 6 which extend longitudinally between each slat, these rows of stitching bringing the opposite sides of the facing together and facilitating the bending of the

section between each slat. The facing covering the upper and lower sides of the slats is secured preferably by a binding 7 which is stitched or otherwise secured to the facing and surrounds the edges of the slats as shown in Fig. 6.

In order to protect the facings of the mat sections from soiling by reason of the spilling of liquids thereon, it is preferable 10 to provide a cover 8 for each section, this cover being composed of linen or other appropriate material or fabric which is in the form of a pocket or case, the case being preferably left open at one edge to permit 15 the insertion and removal of the part containing the slats. These cases will intercept liquids which might otherwise soil the facings of the slats, and by removing the slat portions from the cases, the latter may 20 be readily laundered. By making these cases of fabric or other flexible material, it is possible to roll the sections without removing the cases.

The mat sections are preferably provided 25 with means for joining their adjacent edges to prevent displacement thereof, and for this purpose, the cases in the present instance are provided with suitable means, such as the hook and eye connections 9 which may be 30 connected as the mat sections are placed in position, although these hook and eye connections enable the mat sections to be readily detached when desired.

By making the mat in sections which 35 conform in shape and size to the leaf and end sections of a table, the mat may be readily enlarged or reduced in size so as to properly cover the surface of the table as the leaves are added and removed therefrom, and by making the mat sections each 40 of a series of narrow slats having parallel longitudinal edges, the sections may be rolled or unrolled with the greatest facility, and when in rolled condition, there is very 45 little liability of cracking or injuring the slats. It is generally preferable to construct the slats of asbestos, as the heat insulating properties thereof well adapt it for use in this connection, as the heat from the 50 hot dishes placed upon the table cannot penetrate the mat and reach the polished surface of the table. The cases for inclosing and protecting the mat sections from

soiling may, of course, be omitted, but it is generally desirable to use them, as these 55 cases may be readily removed and laundered, enabling the mat to present at all times a neat appearance.

I claim as my invention:—

1. A heat insulating mat to be removably 60 applied to a table top to protect it, embodying a substantially semi-circular section composed of a series of narrow slats of asbestos arranged in parallel relation and having their ends terminating at the curved margin 65 of the section, a fabric facing applied to the upper and lower sides of the slats and connecting them, the margins of the mat section confining both ends of the slats to prevent their displacement, and lines of stitching 70 uniting the upper and lower sides of the facing between the longitudinal edges of the slats, the mat section being freely rollable throughout its length.

2. A table mat embodying a section composed of a series of narrow slats of heat insulating material having parallel longitudinal edges, a flexible facing covering the upper and lower sides of the slats, the margins of the facing confining the ends of the 80 slats, the longitudinal edges of the respective slats being spaced from one another, and parallel lines of stitching uniting the upper and lower sides of the facing between the slats and serving to facilitate rolling of 85 the section from end to end.

3. A table mat comprising a section made up of a series of narrow slats of asbestos, the longitudinal edges of each slat being parallel and the slats being arranged in 90 parallel relation, a fabric facing covering the upper and lower surfaces of the slats, both ends of the slats being confined at the margins of the mat section, and a line of stitching uniting the upper and lower sides 95 of the facing between the adjacent longitudinal edges of the slats, the slats extending transversely of the section and permitting rolling thereof throughout its length.

In testimony whereof I have hereunto set 10 my hand in presence of two subscribing witnesses.

HARLEY M. KAYLOR.
